CLAIM

The ornamental design for a bottle cap remover, as shown and described.

DESCRIPTION

FIG. 1 is a bottom, front, left side perspective view of a bottle cap remover in accordance with the present invention;

FIG. 2 is a front view of the bottle cap remover shown in FIG. 1;

FIG. 3 is a rear view of the bottle cap remover shown in FIG. 1;

FIG. 4 is a top view of the bottle cap remover shown in FIG. 1;

FIG. 5 is a bottom view of the bottle cap remover shown in FIG. 1;

FIG. 6 is a left side view of the bottle cap remover shown in FIG. 1; and

FIG. 7 is a right side view of the bottle cap remover shown in FIG. 1.

FIG. 8 is a bottom, front, left side perspective view of a second embodiment of the present invention;

FIG. 9 is a front view of the bottle cap remover shown in FIG. 8;

FIG. 10 is a rear view of the bottle cap remover shown in FIG. 8;

FIG. 11 is a top view of the bottle cap remover shown in FIG. 8;

FIG. 12 is a bottom view of the bottle cap remover shown in FIG. 8;

FIG. 13 is a left side view of the bottle cap remover shown in FIG. 8; and,

FIG. 14 is a right side view of the bottle cap remover shown in FIG. 8.

The broken lines in FIGS. 1, 2, 3, 8, 9 and 10 are included to show portions of the bottle cap remover that form no part of the claimed design.

1 Claim, 10 Drawing Sheets
